TURNBUCKLE BODY

Tosiji Asano, Tokyo, Japan, assignor to Asano Bolt
Nuts Co., Ltd., Tokyo, Japan

Filed Dec. 4, 1974, Ser. No. 529,474

Claims priority, application Japan June 12, 1974

Term of patent 7 years

Int. Cl. D8—08

U.S. Cl. D8—229

FIG. 1 is a perspective view of a turnbuckle body showing my new design;

FIG. 2 is a top plan view thereof;

FIG. 3 is a side elevational view thereof;

FIG. 4 is an elevational view taken from one end thereof;

FIG. 5 is an elevational view taken from the end opposite that shown in FIG. 4;

FIG. 6 is a cross sectional view taken on line VI—VI of FIG. 2; and

FIG. 7 is a reduced scale top plan view thereof.

The broken line representation of a connecting rod in FIG. 7 is for purposes of illustration only.

I claim:

The ornamental design for a turnbuckle body, as shown and described.
